UNITED STATES PATENT OFFICE.

CHARLES HENRY ATKINS, OF SPRINGFIELD, MASSACHUSETTS.

CLOTH-TAKE-UP MECHANISM FOR LOOMS.

No. 858,052.

Specification of Letters Patent.

Patented June 25, 1907.

Application filed July 16, 1906. Serial No. 326,380.

To all whom it may concern:

Be it known that I, CHARLES HENRY ATKINS, a citizen of the United States of America, and a resident of Springfield, in the county 5 of Hampden and State of Massachusetts, have invented certain new and useful Improvements in Cloth-Take-Up Mechanism for Looms, of which the following is a full, clear, and exact description.

This invention relates to improvements in cloth take-up mechanism for looms, and more particularly pertains to a novel take-up motion for a loom especially constructed for weaving fine wire cloth, such as employed 15 for the wet pulp web carrier in a Fourdrinier paper machine. The invention is not necessarily confined, however, to a wire weaving loom.

Under an approved manner of weaving 20 fine wire cloth, the lay has its battening strokes or blows up to the cloth line and as limited thereby, and at whatever position such line may happen to be,—the beating-up movements of the lay being under the im- 25 pulse of the more or less elastic force with the tendency of sometimes terminating not so far forward as at other times.

An object of this invention is to provide 30 a take-up mechanism including variable speed imparting means, with provisions for controlling such variable speed imparting means from, or by, the extents of beating up movements of the lay, so that the cloth-beam will have its very slow and gradual rotations at such rate of speed as to maintain 35 the cloth line at substantially the same place just back of the breast roll; and in the carrying out of this object, if the cloth line becomes abnormally rearward, the cloth-beam 40 is automatically caused to have its turning or taking-up movement slightly accelerated, or if there is a tendency of the made cloth to be too far advanced toward the breast roll, the tendency is automatically induced in the 45 take-up-beam for a slightly retarded motion.

And another object of the invention is to provide a take up mechanism suitable for looms of most common description and generally used, which is most satisfactory and 50 desirable by reason of its simplicity and the inclusion therein of the means constructed on approved mechanical principles.

The invention consists in a loom, of a combination with the swinging lay and the cloth-beam, of a shaft having a rotation imparting connection with said cloth-beam, variable

speed driving means for said shaft, and means variably movably actuated by the lay according to the extents of the beating-up movements of the latter, and controlling 60 said variable speed guiding means.

The invention may be otherwise stated to consist in combinations and arrangements of parts as hereinafter described and set forth in the claims.

The improved cloth take-up mechanism is illustrated in the accompanying drawings, in which,—

Figure 1 is a plan view of sufficient of a loom to show the location thereon of the new 70 mechanism in connection with the parts of the loom with which it intimately coacts. Fig. 2 is a one side view of the loom showing the cloth-beam take-up mechanism as seen in elevation thereon. Fig. 3 is an elevation 75 as seen from the opposite side of the loom. Fig. 4 is substantially a vertical sectional view, on a larger scale, through an important part of the novel mechanism hereinafter particularly referred to. Fig. 5 is a cross sec- 80 tional view as taken on the line 5—5 on both Figs. 2 and 4. The section line 4—4, on Fig. 5, indicates the plane on which the section Fig. 4 is taken.

The drawings, Figs. 1, 2, and 3, show a 85 warp let-off motion invented by me, and forming the subject of a separate application for Letters Patent of the United States filed of even date herewith, and not herein particularly referred to.

Similar characters of reference indicate corresponding parts in all of the views.

In the drawings,—A represents the loom frame of which *a a* are the loom sides.

B indicates the warp beam, C the cloth 95 beam, D the breast roll, E the lay, and *x* indicates the warp wires with the shed converging to the cloth line just to the rear of the breast roll indicated in the side views at the point *y*.

The cloth-beam C has a worm wheel F affixed thereon, and adjacent the edge of said worm wheel F is a suitably journaled, and supported, axially vertical, shaft G having a worm H affixed thereon and in mesh with 105 the cloth-beam worm-wheel F. The said shaft G has a portion formed screw-threaded, as indicated at *b*, such threads being of ratchet shape in the present instance.

So far as the present invention is concerned, J may be regarded as the primary driving shaft, the same being by bevel gear-

ing *c* connected with the vertical shaft *K* having an upwardly tapering cone pulley *L* thereon. Parallel and suitably separated from the shaft *K* is another vertical shaft *M* having affixed thereon a cone pulley *N*, the taper of which is downward; and the said shaft *M* has a worm *d* affixed thereon which is in mesh with the worm wheel *e* on the short horizontal shaft *f*, which by bevel gearing *g*, *g*², is in driving connection with the aforementioned shaft *G* on which are the worm *H* and the threaded portion *b*. A belt *O* runs around and between the reversely tapered cone pulleys *L* and *M*; and *P* represents a shifter for said belt, the same being pivotally hung at *h* on a suitable bracket therefor.

It will be apparent that if the belt *P* is moved upwardly relatively to the widening portion of the cone pulley *N*, and the narrow portion of the pulley *L*, a retardation in the driving speed of the cloth beam rotating connections will result, the reverse being true when the belt is shifted downwardly relatively to the said cone pulleys.

Q represents a sleeve like nut carrier slidable vertically relatively to the threaded portion of said shaft *G*, and one or more nut sections *i*, *i*² are provided to, and supported by, the said carrier and have detachable engagements with the ratchet shaped threads of the said shaft *G*.

The nut sections, as shown, are made in the form of levers intermediately pivoted at *j*, *j*² to the sleeve like nut carrier within opposite vertical recesses therein; and these nut sections are by the springs *k* forced so that their toothed or thread engaging members *i*² will be kept in engagement with the threads *b* of the said shaft *G* whereby the rotation of such shaft will cause a downward feeding of the nut engaged part *Q*.

R represents a rod between and connected with the upper end of the nut carrier *Q* and an intermediate part of the belt shifter *P*; and as indicated by the screw threaded formations *m*, *m*², engaged in sockets in the connection sections *n*, *n*², this rod is in substance longitudinally distensible and contractible whereby may be adjusted, for proper working of the mechanism, the relations between the nut carrier and the belt shifter.

S, *S*² represent a two membered lever mounted at the side of the loom, the member *S* being inwardly offset from the member *S*², the one being inside of the loom frame while the other is at the exterior thereof, the parts being united by the integrally or rigidly affixed pivoted stud *o*.

The member *S* is formed with an upwardly inclined forward portion *p* normally in the path of, and to be impinged against by, a projection or roller *q* on the side of the lay,— the same being carried, for instance, on a depending extension of one of the lay swords.

The other arm *S*² of the said two membered lever is bifurcated to straddle an intermediate portion of the nut carrier *Q*, and has approaching studs *r* which engage in the opposite side recesses in the nut carrier.

The lay moving forwardly engages the lever *S*, *S*², and swings the same more or less accordingly as the extent of the swing of the lay is excessive, or of scant extent. If cloth has been well taken up and the beating up point is pretty well forward, the lay, in coming to the comparatively considerably forward point will swing the lever considerably and thereby considerably raise the nut carrier, the nut and the belt shifter, placing the belt on the larger portion of the tapered pulley *N*, and the nut on a higher screw threaded portion of the shaft; and the screw and worm will be slightly retarded in their movements, with corresponding effect on the very slow taking up rotative movement of the cloth-beam.

The screw *b* constantly feeds the nut, and its carrier, in a downward direction, and moves the belt shifter in a downward direction, thus automatically insuring a running at a slightly increasing speed of the feed mechanism for the cloth-beam, but as above explained, whenever such feeding or taking up of the cloth beam becomes too much advanced, the action by the lay on the swinging lever, and through it on the nut, nut carrier, and belt shifter, is such as to insure a retardation in the driving of the cloth take-up mechanism.

The motion imparting mechanism for the cloth-beam is sufficiently duplicated so that the cloth-beam has rotative winding-up movements positively and concurrently imparted thereto at both ends of the beam, it being perceived that the shaft *M* is at its upper end, by bevel gearing *v*, connected with a horizontal transverse shaft *T*, which in turn by bevel gearing *v*² drives a shaft *M*² at the opposite side of the loom, which shaft has a worm *d*² meshing into the worm wheel *e*² on short shaft *f*² and which by bevel gearing *g*³ drives a short vertical shaft *G*² having a worm *H*² which is in mesh with the worm wheel *C*² on the other end of the take-up beam, it being, of course, apparent that no necessity exists for a duplication of the lever *S*, *S*², the nut carrier and nut, screw threaded shaft portion *b*, belt shifter and cone pulley drive.

I claim:

1. The combination with the cloth-beam of a loom, of a shaft having a rotation imparting connection with said cloth-beam, variable speed driving means for said shaft, and means, actuated by the lay according to the extents of its beating up movements, and controlling said variable speed driving means.

2. The combination with the cloth-beam of a loom, of a shaft having a rotation imparting connection with said cloth beam, va-

- riable speed driving means for said shaft, a screw rotatable in unison with said shaft, and a nut having detachable engagement with said screw, a carrier for the nut, means variably movably actuated by the lay according to the extents of its beating up movements, and controlling the position of said carrier and nut, and means connected with said carrier, and to have changed positions in unison therewith, and automatically controlling the said variable speed driving means.
3. The combination with the cloth-beam of a loom, of a shaft having a cone pulley thereon, and having a rotation imparting connection with said cloth-beam, a belt running around and driving said cone pulley, a shifter for said belt, a screw rotatable in unison with said shaft, and a nut having detachable engagement with said screw, a carrier for the nut, connected with said belt shifter, and means variably movably actuated by the lay according to the extents of its beating up movements, and controlling the position of said carrier nut.
4. The combination with the cloth-beam of a loom, of a shaft having a rotation imparting connection with said cloth-beam, variable speed driving means for said shaft, a screw rotatable in unison with said shaft, and a nut having detachable engagement with said screw, a carrier for the nut, a lever mounted for a swinging movement, having a portion thereof in the path of, and to be successively engaged, and to be more or less swung, by the lay according to the extents of the beating up movements, and said lever having connection with the nut carrier, and means connected with said carrier and to have changed positions in unison therewith, and controlling the said variable speed driving means.
5. The combination with the cloth-beam of a loom, of a shaft having a rotation imparting connection with said cloth-beam, and having screw-threads on a portion thereof, variable speed driving means for said shaft, a sleeve like part slidable on said shaft and having, supported thereby, a nut section engaging said screw threads, a lever, to be successively engaged and swung by the lay and having an engagement with said sleeve like part, and a connection between said sleeve like part and the said variable speed driving means.
6. The combination with the cloth-beam of a loom, of a shaft having a rotation imparting connection with said cloth-beam, and having ratchet shaped screw-threads on a portion thereof, variable speed driving means for said shaft, a sleeve like part slidable on said shaft and having, intermediately pivotally mounted thereon a lever like nut section, normally spring pressed with a toothed member thereof in engagement with said screw threads, a lever, to be successively engaged and swung by the lay and having an engagement with said sleeve like part, and a connection between said sleeve like part and the said variable speed driving means.
7. The combination with the cloth-beam of a loom and the shaft having a rotation imparting connection with said cloth-beam, and having screw threads on a portion thereof, another shaft having a driving connection with said first named shaft provided with a cone pulley, a belt running around and shiftable relatively to said cone pulley, means for driving said belt, and a shifter for said belt, a nut carrier slidable on said screw threaded shaft, having a nut engaging in the screw threads thereof, a lever to be successively engaged and swung by the lay and having an engagement with said nut carrier, and a longitudinally adjustable connecting rod between said nut carrier and said belt shifter.
8. In combination, the cloth beam of a loom having a worm wheel affixed thereon, a shaft having a screw threaded portion, also having a worm in mesh with said worm wheel and having an affixed bevel gear wheel, a shaft having a bevel gear wheel meshing with the first named bevel gear wheel, and having a worm wheel, another shaft having a worm in mesh with the last named worm wheel and having a cone pulley, a still further shaft having a reversely tapered cone pulley, and means for constantly rotating it, a belt running around and between both said cone pulleys, a shifter for said belt, a nut carrier slid able along said screw threaded shaft and having a nut detachably engaged with the threads thereof, a two membered lever pivotally mounted on the side of the loom having one member thereof in the path of, and to be successively engaged by, the forwardly swinging lay, and having the other member in engagement with the said nut carrier, and a connection between said nut carrier and the belt shifter.

Signed by me at Springfield, Mass., in presence of two subscribing witnesses.

CHARLES HENRY ATKINS.
